UNITED STATES PATENT OFFICE

HANS LUFT, OF NEWARK, NEW JERSEY

LINKED BRACELET

Application filed December 15, 1927. Serial No. 240,158.

The invention is a bracelet in which the links are hinged together to provide a limited flexibility to the bracelet and one in which the links can be easily connected together or separated without the use of tools, thus providing for a quick and cheap assembling of the bracelet and also providing a ready means for altering the length of the bracelet as when the bracelet is to be fitted to the wrist.

10 The invention provides a bracelet that preferably has a one-piece casing for each link the casing containing two pieces, one a sliding connecting piece and the other a spring to yieldingly hold the connection in

15 the casing.

The invention is illustrated in the accompanying drawing in which Figure 1 is a top view and Figure 2 is a side view of a bracelet embodying my invention. Figure 3 is a bottom view of the bracelet with several links shown in section. Figure 4 is a longitudinal central section of the bracelet, and Figure 5 is bottom view of two links and showing in section a connection of a third link. Figure 6 is a side view and Figure 7 an end view of links in position to be separated. Figure 8 is a perspective view of a staple preferably used as a connection between the links and Figure 9 is a face view of the blank from which the casing is made.

The bracelet consists of links which are made up of a blank as shown in Figure 9. The part 10 forms the top and the part 11 forms the bottom of the casing. The wings 35 12 form the side walls and the dips 13 are bent over to secure the parts in place. The strip 14 forms one end wall and the strip 15 forms the other end wall.

The blank is first bent at 16 to set up the 40 side walls and at 17 to set up the end wall 15 and at 18 to set up the wall 14. Then the connection (to be hereinafter described) is placed in the casing and the bottom folded over on the scored part 19. This latter is 45 usually done by hand by simply squeezing the parts between the thumb and finger.

The connection is usually in the form of two 50 arms 20 which are connected together, generally by a cross-piece 21 so that the article is in the form of a staple. This staple slides in

the casing and is held retracted by the spring 22 or similar spring placed between the arm 21 and end wall 14. Other forms and locations of yielding holding means can be employed. The arms 20 can thus be slid from one end of the link and have studs 23 which are placed in the side walls at the other end of the next succeeding link.

55 The arms 20 fit between the end wall 14 and the side walls 12 as will be seen from Figures 2 and 5 and cannot move laterally when the bracelet is straight or slightly flexed. When the links are swung to abnormal position relative to each other the end of the staple or arms 20 can be squeezed together to withdraw the 60 studs 23 from the holes 24.

65 This is possible because when one of the links is pulled back on its staple as shown to the left of Figure 6 and in end view Figure 7 and then swung around at an acute angle to 70 the nearest link the ends of the staple can be supported between the thumb and finger on account of the widened slot 25 formed in this end of the link by cutting away the bottom plate as shown at 26 in Figure 9. The reverse 75 operation is done in assembling the links, the staple of one link being pulled out and held with its ends slightly bent toward each other which nature of the metal allows and placing through the widened slots 80 as shown in Figure 6 and then released to allow the studs 23 to snap into the holes 24 of the next link. The links are then swung to normal position relative to each other and are thus held together in hinged relation as 85 the end wall 14 prevents the inward movement and consequent disengagement of the arms 20.

I claim:—

1. In a bracelet, a link comprising a casing, 90 a staple having arms slidable from one end of the casing and projections on said arms, the casing having perforations on the other end to receive the projection of the staple in the next link, the link having the bottom 95 plate cut away to permit the arms of the staple of the next link to be flexed in the assembling or separation of the links.

2. In an extensible bracelet, a link comprising a casing, a staple having arms slid- 100

able from one end of the casing and projections on said arms, the casing having perforations on the other end to receive the projections of the staple of the next link, the link having the bottom plate cut-away to permit the arms of the staple of the next link to be flexed in the assembling or separation of the links and a spring for yieldingly holding the staple in retracted position.

10 3. In an extensible bracelet, a link comprising a hollow casing, a pair of connected arms in the casing and slidably from one end thereof, a spring to hold the arms in retracted position, studs on the outside of the ends of
15 the arms, the casing having at its other end a slot on each side which slots extend into and are widened on the bottom plate of the casing and having perforations in the sides at said other end.

20 In testimony whereof I affix my signature.
HANS LUFT.
